UNITED STATES PATENT OFFICE.

WILLIAM LINDSAY, OF CHICAGO, ILLINOIS.

AEROPLANE PROPELLER.

1,421,699.

Specification of Letters Patent. Patented July 4, 1922.

Application filed June 19, 1918. Serial No. 240,745.

To all whom it may concern:

Be it known that I, WILLIAM LINDSAY, a citizen of the United States, and resident of the city of Chicago, in the county of 5 Cook and State of Illinois, have invented a certain new and useful Aeroplane Propeller, of which the following is a specification.

This invention relates to aeroplane propellers, and its principal object is to provide a simplified, efficient and improved propeller, wherein the gyrostatic and cross-sectional strains in the blades, normally caused by the variation from the line of flight and 15 by the thrust and drift forces, will be greatly decreased, the thickness or volume of the blades consequently reduced, and an improved mode of operation of the blades, resulting in high increase of the efficiency of 20 the propeller, attained.

Another object is to provide a strong, durable, and conveniently manufacturable and utilizable propeller, wherein the blades are interchangeable and may be individually replaced in case any damage occur to any one of them.

In carrying out the invention, individual blades are independently pivoted to the hub of the propeller in such manner that they 30 may be also secured to the hub against swinging, so as to be converted into a rigid propeller. When the blades are in pivoted state, they will during rotation of the propeller dispose themselves along a line which 35 is the resultant of the centrifugal and thrust forces, in which position they may also be permanently secured to the hub, and in either of which cases the cross-sectional strains will be minimized, the great reduction 40 of the thickness of the blades rendered possible, and the resulting efficiency of the propeller secured. The blades are also disposed along a line which is the resultant of the centrifugal and drift forces, which further minimizes the strains and results in 45 a consequent reduction in the volume of the propeller and a further increase of the efficiency thereof.

As a result of the stated disposition of 50 the blades, their cross-sectional area may be reduced to such an extent that it enables constructing the entire propeller of metal, and thereby affords the various advantages which a propeller of metal would have 55 over a wooden propeller, such as increased efficiency, inherent strength, and durability.

Other objects and advantages will herein-after appear.

In the accompanying drawings,—

Fig. 1 shows a side elevation of the aeroplane propeller. 60

Fig. 2 shows a plan view of the propeller shown in Fig. 1.

Figs. 3, 4, and 5 show modifications of the propeller. 65

The drive-shaft 1 of the aeroplane carries a hub 2 provided with two pairs of ears 3, and between each pair of ears is lodged the extremity 4 of the base 5 of a propeller-blade 6. A bolt 7 passes through 70 each pair of ears 3 and through the extremity 4 of its blades 6, whereby the blade is pivotally held to the hub 2 and is swingable about its bolt 7 toward and away from the direction of flight of the aeroplane. 75 For each blade 6 is provided a spring 9, which is secured to the hub 2 at 10 and also to the blade at 8, thereby maintaining said blades in extended position when in inoperative state. 80

When the propeller is in operation, the centrifugal force tends very strongly to maintain the pivoted blades 6 revolving in a plane which is rightangular to the direction of flight, while on the other hand the thrust 85 tends to swing the blades in a direction which is similar to the direction of flight, and the consequence thereof is that each of the blades becomes disposed angularly, as shown in Fig. 1, along a direction which coincides with the resultant of the centrifugal and thrust forces. Thus in Fig. 1, the arrow 11 represents the direction of flight, the dash and dot line 12, which is rightangular to the direction of flight, represents the direction and magnitude of the centrifugal force, the line 13, which is parallel to the direction of flight, represents the direction and magnitude of the thrust, and the line 14, which is the centre line of gravity of 90 the blade 6 and completes the triangle with or the resultant of the complementary lines 12, 13, represents the resultant or actual disposition of the blade 6, when the propeller 95 is revolving. 100

The effect of the above described action of the blades 6 during operation of the propeller, wherein each blade seeks independently its own plane of revolution, is to minimize greatly the lateral or cross sectional 110 breaking strain at every part of the blade and particularly at its base portion 5, whereby the

thickness of the blade may be reduced to such an extent as to enable casting or forging the entire blade of metal, such as steel or other metal having a high tensile strength, 5 and thus rendering the propeller practically indestructible under all conditions. Constructing the blade 6 of metal enables making further reduction in the thickness of the blade, and each reduction of the thickness 10 of the blade conduces greatly toward increasing its driving efficiency, due to the reduction of the rotational resistance or, what is termed, the drift of the propeller. The pivoted or, what may be termed, the independent 15 flexible connection of each one of the blades 6 with the hub 2 tends to soften the gyrostatic action of the propeller, and results in eliminating considerably the strain caused thereby to the engine drive-shaft 1 and the 20 friction of said shaft in its bearings. When changing the direction of flight of the aeroplane each spring 9 aids in forcing its blade 6 into the new plane of revolution. This mode of connection of blades 6 with the 25 hub 2 also lessens the shock to the propeller and aeroplane, caused by the sudden turning movement of the aeroplane.

If desired, the blades 6 may be secured rigidly to the hub 2, against swinging with 30 relation thereto, in the disposition shown in Fig. 1, by means of strongly tightening the bolts 7 and the nuts 15 and thereby compelling the ears 3 to forcibly grip the bases 4 of the blades, whereupon the blades 6 will 35 continuously remain in the direction of the resultant 14 of the centrifugal and thrust forces 12, 13, as an entirely rigid propeller.

In the direction of revolution of the propeller, Fig. 2, the centre line of gravity of 40 each of the blades 6, rather than being radial to the centre line of the drive shaft 1 as was heretofore the practice, is here disposed angularly, as shown, along a direction which coincides with the resultant of the drift and 45 centrifugal forces. Thus, in Fig. 2, the arrows 16 represent the direction of revolution, the line 17 which is radial to the centre line of the drive shaft 1 represents the direction and magnitude of the centrifugal force, the 50 line 18 represents the rotational resistance or drift, and the line 19, which is the centre line of gravity of the blade 6 and completes the triangle with or the resultant of the complementary lines 17, 18 represents the resultant 55 or actual disposition of the blades 6. The effect of this disposition of the blades 6 is to further minimize, during rotation of the propeller, the cross-sectional breaking strain at every part of the blade, and particularly at its base-portion 5, caused by the 60 drift force or resistance to rotation, whereby the thickness of the blade may be further reduced and the various above mentioned advantages of such reduction obtained.

65 When making the individual blade 6 of

forged metal its base-portion 5 may be split, as shown in Fig. 4, and the opening 20 between the split portions 21 may be filled with any light material such as wood, thereby increasing the width and consequently the 70 strength of the base-portion 5, so that it may be thinned down further and the well known advantages of such reduction of thickness attained. The blade 6 may be also made partially hollow at its base-portion 5, as shown 75 in Fig. 5.

The modification shown in Fig. 3 illustrates the adaptation of the improvements herein to a three-blade propeller.

Variations may be resorted to within the 80 scope of the invention, and portions of the improvements may be used without others.

Having thus described my invention, I claim:

1. An aeroplane propeller having the 85 combination of a hub adapted to be secured to a drive shaft, a plurality of individual blades each of which is constructed of metal and each of said blades being split at its base and filled with lighter non-metallic material.

2. An aeroplane propeller having the longitudinal centre line of its vanes so disposed during flight that it lies in the direction of a line which is the resultant of the 95 thrust, torsional, and centrifugal forces, and said vanes being disposed in operative state when the aeroplane is at rest.

3. An aeroplane propeller having the longitudinal centre line of its vanes so disposed during flight that it lies in the direction of a line which is the resultant of the torsional and centrifugal forces, and said 100 vanes being disposed in operative state when the aeroplane is at rest.

4. An aeroplane propeller having the longitudinal centre line of its vanes so disposed during flight that it lies in the direction of a line which is the resultant of the torsional and centrifugal forces, said vanes being pivoted to permit them to automatically assume a position which is the resultant of the said two forces and also that of thrust, and said vanes being disposed in operative state when the aeroplane is at rest. 110

5. An aeroplane propeller having the longitudinal centre line of its vanes so disposed during flight that it lies in the direction of a line which is the resultant of the torsional and centrifugal forces, said vanes being pivoted to permit them to automatically assume a position which is the resultant of the said two forces and also that of thrust, said vanes being disposed in operative state when the aeroplane is at rest, 120 and means to interchangeably secure said vanes to retain them permanently in the resultant of the said three forces. 125

6. An aeroplane propeller having the longitudinal centre line of its vanes so dis-

105

115

posed during flight that it lies in the direction of a line which is the resultant of the thrust and centrifugal forces, means to permit said vanes to automatically assume a 5 position which is the resultant of the said two forces, said vanes being disposed in operative state when the aeroplane is at rest, and means to interchangeably secure said vanes to retain them permanently in the re- 10 sultant of the said two forces.

7. An aeroplane propeller having the combination of a hub adapted to be secured to a drive shaft, a plurality of individual blades each of which is pivoted directly to 15 said hub without any intervening element and adapted to swing independently without affecting any other blade, and a spring for each of said blades cooperating therewith individually to maintain it extended 20 when in inoperative state.

8. An aeroplane propeller having the combination of a hub adapted to be secured to a drive shaft, a plurality of individual blades each of which is pivoted directly to 25 said hub without any intervening element and adapted to swing independently without affecting any other blade, and a spring for each of said blades cooperating therewith individually to induce the blades in ac- 30 quiring their new place of revolution when changing direction of flight.

9. An aeroplane propeller having the com-

bination of a hub adapted to be secured to a drive shaft, a plurality of individual blades each of which is pivoted to said hub without 35 any intervening element and adapted to swing independently without affecting any other blade, a spring for each of said blades cooperating therewith individually to maintain it extended when in inoperative state, 40 and induce the blades in acquiring a new plane of revolution, said blades being adapted to automatically swing to a position that coincides with the direction of a line which is the resultant of the centrifugal and thrust 45 forces of the revolving propeller, means for each of said blades to fasten it independently to said hub in the said resultant position for operating the propeller with the blades in rigid condition, each of said blades 50 being also disposed whereby its centre line of gravity extends away from a line radial to the centre line of rotation of the propeller and in a direction that coincides with a line which is the resultant of the centrifugal 55 and torsional forces of the revolving propeller, and said blades being adapted to be independently attached to and detached from said hub.

Signed at the city of Chicago, in the 60 county of Cook, and State of Illinois, this 14th day of June, A. D. 1918.

WILLIAM LINDSAY.
